Filed Feb. 21, 1967, Ser. No. 5,906

Term of patent 14 years

(Cl. D58—26)

FIG. 1.

FIG. 2.

FIG. 3.

FIG. 4.

FIG. 5.

FIG. 6.

FIG. 7.

FIG. 8.

FIG. 1 is a front elevational view of a dispensing cap embodying my new design.

FIG. 2 is a rear elevational view thereof.

FIG. 3 is a right side elevational view thereof.

FIG. 4 is a left side elevational view thereof.

FIG. 5 is a top plan view thereof.

FIG. 6 is a bottom plan view thereof.

FIG. 7 is an isometric view thereof showing the spout in the closed position.

FIG. 8 is an isometric view thereof showing the spout in the opened, dispensing position.

The characteristic feature of the design resides in the flat circular top surface portion surrounded by an annular flat portion of substantially equal area disposed a substantial distance beneath the top surface portion, said portions being joined by a straight vertical wall of substantial depth.

I claim:

The ornamental design for a dispensing cap, substantially as shown and described.
